Term of patent 14 years

(Cl. D80—11)

To all whom it may concern:

Be it known that we, Edvin F. Bjoro and John M. Fisher, citizens of the United States, residing at Huntington, L. I., and Village of Huntington Bay, Huntington, L. I., respectively, in the county of Suffolk and State of New York, have invented a new, original, and ornamental Design for a Display Cabinet, of which the following is a specification, reference being had to the accompanying drawing, forming a part thereof.

Fig. 1 is a front perspective view of a display cabinet, showing our new design; Fig. 2 is a front elevational view thereof; and Fig. 3 is a side elevational view.

This application is a division of application Serial No. D. 128,172, filed April 2, 1946.

We claim:

The ornamental design for a display cabinet, as shown.

EDVIN F. BJORO.
JOHN M. FISHER.
